AMPLIFIER FOR ELECTRONS

René Barthelemy, Fontenay aux Roses, France,
assignor to Compagnie pour la Fabrication des
Compteurs et Matériel d'Usines A Gaz, Mont-
rouge, Seine, France

Application August 10, 1937, Serial No. 158,350
In France August 28, 1936

8 Claims. (Cl. 250—166)

Electron multipliers have already been constructed which are composed of a series of photo-sensitive plates and in which the electrons emitted by the first electrode or cathode are projected onto a second plate, by means of electric and magnetic fields, and give rise to secondary electrons which are in their turn projected onto another electrode, etc.

A considerable amplification of the primary effect is thus obtained.

However, for very weak incident light it has been observed that in the output current of the tube there exists a large number of disturbances or irregular oscillations of short duration which form a troublesome "Schott" effect which is far greater than that foreseen in theory. This effect exists in the absence of any luminous excitation.

The present invention enables this drawback to be to a great extent overcome. It has been observed that the said phenomena vary in frequency and in intensity with the arrangement and the nature of the insulating supports of the electrodes and the proximity of mica plates laterally limiting the chain of electronic targets.

In order to avoid the projection of electrons which can produce harmful charges in these surfaces and supports, the novel device provides for the creation of one or a plurality of equipotential surfaces which are definitely negative relatively to the successive cathodes or electrodes, and arranged laterally in such a manner that they repel the electrons towards the longitudinal axis of the amplifying system.

The invention is illustratively exemplified in the accompanying drawings, in which

Figs. 1 and 2 show two embodiments of the invention in perspective views,

Fig. 3 is a perspective view of a modified device according to Fig. 1,

Figs. 4 and 5 illustrate two additional embodiments in cross-sections, and

Fig. 6 is a perspective view of a modification of Fig. 2.

The amplifier comprises a bulb B within which the first photo-electric cathode K₁, Fig. 1, receives the outer light and the electrons emitted are attracted by an electric field existing between the upper plate R₁ and the cathode. Any known means such as M₁ M₂ produce a magnetic field perpendicular to the path of the electrons, which magnetic field bends their trajectory and causes them to fall on to the following cathode K₂ which then emits secondary electrons in greater number. This known arrange-

ment is repeated several times by means of the following plates which are raised to suitable potentials and by means of the magnetic field. The cathodes K₁, K₂, etc. and the plates R₁, R₂, etc. are raised to suitable potentials by the connections N₁, N₂, etc. and P₁, P₂, etc.

The improvement which is the object of the present invention consists in arranging two lateral electrodes C₁, C₂ of elongated shape which are raised in general to a potential substantially equal to or less than that of the first cathode K₁ by means of connection Q₁ and F₁. The action of these additional electrodes has the effect of preventing the electrons from being precipitated out of the parallelopiped limited by the cathodes K₁, K₂, etc. and the repulsion plates R₁, R₂, R₃, etc.

A kind of conducting tube C₃, Fig. 4, can also be arranged entirely surrounding the amplifying system. Said auxiliary electrodes or said conducting tube can be placed outside the glass tube containing the amplifier (see Fig. 5), in the immediate proximity of the tube itself, or in contact with same.

According to another embodiment of the invention, Fig. 2, the auxiliary lateral electrodes are divided into a plurality of sections C'₁ C''₁ C'₂ C''₂ raised to suitable potentials relatively to the successive cathodes by the connection Q₁, Q₂, etc., and F₁, F₂, etc.

It has been found on the other hand that the harmful effects decrease with the surface of the electrodes K₁ K₂ R₁ R₂.

Trouble however is encountered in this connection owing to the difficulty in concentrating on a small surface the incident light which in general comes from a televised scene. A complementary improvement enables the surface of the first cathode to be considerably reduced: it consists in placing inside the tube itself and adjacent the upper electrode, a lens of short focal length L (see Figs. 3 and 6) or any appropriate optical system which, when it is outside the tube, cannot generally be placed sufficiently near said cathode.

What I claim is:

1. An electron multiplier tube comprising a succession of cathodes, a succession of accelerating electrodes parallel to said cathodes, and auxiliary electrodes adapted to be raised to a lower potential than that of the first of said cathodes, said auxiliary electrodes being mounted on either side of said cathodes and accelerating electrodes and closing the space between the

group of cathodes and the group of accelerating electrodes.

2. An electron multiplier tube comprising a succession of cathodes, a succession of accelerating electrodes parallel to said cathodes, and two auxiliary half-tubular electrodes adapted to be raised to a lower potential than that of the first of said cathodes, said auxiliary electrodes surrounding said cathodes and accelerating electrodes and closing the space between the group of cathodes and the group of accelerating electrodes.

3. An electron multiplier tube comprising a succession of cathodes, a succession of accelerating electrodes parallel to said cathodes, and two groups of auxiliary electrodes mounted respectively on either side of said cathodes and accelerating electrodes and closing the space between the group of cathodes and the group of accelerating electrodes, each of said auxiliary electrodes being adapted to be raised to a lower potential than the potential of the cathode which is adjacent same.

4. An electron multiplier tube comprising a succession of cathodes, a succession of accelerating electrodes parallel to said cathodes, and two auxiliary electrodes adapted to be raised to a lower potential than that of the first of said cathodes and mounted on either side of said cathodes and accelerating electrodes, outside said tube, for maintaining all the electrons in their path from one cathode to the following cathode.

5. An electron multiplier tube comprising a succession of cathodes, a succession of accelerating electrodes parallel to said cathodes, auxiliary electrodes mounted on either side of said cathodes and accelerating electrodes and closing the space between the group of cathodes and the group of accelerating electrodes, said auxiliary

electrodes being adapted to be raised to a lower potential than the potential of the first cathode, and an optical system mounted within said tube adjacent the first of said cathodes to concentrate light on said first cathode.

6. An electron multiplier tube comprising a succession of cathodes, a succession of accelerating electrodes parallel to said cathodes, two groups of auxiliary electrodes mounted respectively on either side of said cathodes and accelerating electrodes and closing the space between the group of cathodes and the group of accelerating electrodes, each of said auxiliary electrodes being adapted to be raised to a lower potential than the potential of the cathode which is adjacent same, and an optical system mounted within said tube adjacent the first of said cathodes to concentrate light on said first cathode.

7. An electron multiplier tube comprising a succession of cathodes, a succession of accelerating electrodes parallel to the said cathodes and auxiliary electrodes mounted on either side of and perpendicularly to said cathodes and accelerating electrodes and being adapted to be raised to a suitable potential to maintain all the electrons in their path from one cathode to the following cathode.

8. An electron multiplier device comprising a container, a succession of cathodes and a succession of accelerating electrodes parallel to the said cathodes in said container, and auxiliary electrodes mounted outside said container on either side of and perpendicularly to said cathodes and accelerating electrodes and being adapted to be raised to a suitable potential to maintain all the electrons in their path from one cathode to the following cathode.

RENÉ BARTHELEMY.
